UNITED STATES PATENT OFFICE.

EZRA NICHOLSON, OF CLEVELAND, OHIO.

REGISTERING DEVICE.

No. 927,065.

Specification of Letters Patent.

Patented July 6, 1909.

Application filed October 10, 1907. Serial No. 396,840.

To all whom it may concern:

Be it known that I, EZRA NICHOLSON, a citizen of the United States of America, residing at Cleveland, in the county of Cuyahoga and State of Ohio, have invented certain new and useful Improvements in Registering Devices; and I hereby declare the following to be a full, clear, and exact description of the invention, such as will enable others skilled in the art to which it pertains to make and use the same.

This invention relates to new and useful improvements in registering devices and particularly for indicating the distance traveled by vehicles and especially automobiles.

The object of this invention is to provide an electrically actuated device of this character which will be simple and durable in construction, and accurate in its operation.

A further object of my invention is to provide a device of this character which will also serve the purposes of a speedometer.

My invention, therefore, consists in the features of construction and combination of parts as described in the specification, pointed out in the claim and illustrated in the accompanying drawings.

In the accompanying drawings Figure 1 is an outside view of the device. Fig. 2 is a view of same with dial removed and casing in section. Fig. 3 is a section on line 3—3, Fig. 2. Fig. 4 is a section on line 4—4, Fig. 2. Fig. 5 is a detail view showing the method of mounting the contact making device on a machine. Fig. 6 is a side view of same. Fig. 7 is a section on line 7—7, Fig. 6.

Again referring to the drawings 1 represents the outer casing of the device which is preferably circular in form. At the back of the casing is arranged a plate 2 on which are mounted a pair of standards or brackets 3. In the brackets 3 is rotatably mounted a small shaft 4 and on the shaft 4 is secured a worm 5 and a ratchet wheel 6. Centrally in the casing and below the shaft 4 and at a right angle thereto is arranged a shaft 10, one end of which is journaled in the plate 2 and the other end is journaled in a bracket 11 which is secured to said plate 2. On the shaft 10 is rigidly secured a gear wheel 12 which is arranged to mesh with the worm 5 and also a bevel gear 13. In proximity to the shaft 10 is arranged a registering device 14 of any of the usual forms now on the market and commonly termed cyclometers, the construction and operation of which are so well known that detail description thereof is not deemed necessary. The cyclometer 14 is so arranged that the shaft 15 thereof is at a right angle to the shaft 10 and thereon is rigidly secured a bevel gear 16 which meshes with the bevel gear 13 on the shaft 10.

It will be readily seen that when the shaft 4 is rotated the worm 5 thereof will drive the gear wheel 11 on the shaft 10 thereby operating said shaft 10 and the bevel gear 13 thereon, which in turn drives the bevel gear 16 on the cyclometer shaft, thereby actuating the cyclometer. In the bottom of the casing is mounted an electro-magnet 20 and above the electro-magnet is hinged an armature or plate 21. A coil spring 22 is connected to the plate 21 and to one of the brackets 3 so as to normally hold the plate out of contact with the pole of the electro-magnet. On the plate 21 is pivotally mounted a pawl 24 which is arranged to engage with the ratchet wheel 6 on the shaft 4. A small pin 25 extends at a right angle from the pawl 24 and a spring 26 is mounted on the plate 21 and engages with the said pin 25 so as to hold the pawl yielding against the ratchet wheel 6. When the electro-magnet 20 is energized it will attract the plate 21 causing it to move down and the pawl 24 is drawn over the teeth of the ratchet wheel 6 and drops down behind a tooth. When the magnet ceases to be energized the spring 22 pulls up the plate 21 causing the pawl 24 to move up and being in engagement with the ratchet wheel 6 it causes a movement of the wheel and a consequent rotation of the shaft 4. A stop 23 is provided for limiting the upward movement of the plate 21. A flat spring 27 is arranged to press against the hub of the ratchet wheel 6 to serve as a brake and prevent the wheel moving more than one tooth at each impulse of the pawl. At one side of the casing are mounted two switch blades 29 and 30, preferably, formed of strips of some resilient material, such as copper or brass. The blades are mounted on a block of insulating material 31 so that the ends of the said blades are normally held apart. One of said blades is preferably provided with a contact point 32. In proximity to the said switch blades 29 and 30 is mounted a switch key 33 formed of some insulating material and having a cam head 34 so that when the key is turned in one position it will clamp the switch blades together and when turned in the other position it will permit the blades to

separate. One terminal of the electro-magnet is connected to a binding post 35 and the other terminal of the magnet is connected to the switch blade 29. The other blade 30 of 5 the switch is connected with a binding-post 36. To the binding-posts 35 and 36 are secured flexible tongues or strips of copper 37 and 38 and to these tongues are secured the wires 39 and 40 which form the circuit of the 10 battery 41 and the contact maker. I prefer to use these strips as I have found that where the wire is connected directly to the binding-post the jarring or shaking of the machine breaks the wires where they are clamped to 15 the posts while when the wires are connected to the flexible strips this does not happen. The case 1 is provided with a dial face 42 on which are set forth characters to indicate multiples of miles and in the dial face of the 20 cyclometer is formed an opening 43 through which the figures on the cyclometer may be read. The shaft 10 projects through at the center of the dial and thereon is mounted a hand or pointer 44.

25 In Figs. 5, 6 and 7 wherein is shown the contact maker and the portion of the machine on which it is mounted 45 represents the hub of one of the wheels of the machine and 46 represents the steering knuckle. On 30 the steering knuckle is mounted the contact maker which comprises two clamping members 47 and 48 which are preferably formed of some insulating material. The member 47 is in the form of a rectangular plate and is 35 arranged to embrace the steering knuckle and the member 48 is made comparatively narrow and is secured to the member 47 by bolts 49. Switch blades 50 and 51 are secured to the member 48 on opposite sides 40 thereof. The blades are formed of some thin flexible material and one of the said blades is preferably provided with a contact point 52. Flexible strips of copper or other suitable material 55 and 56 are mounted on the clamp 45 member 48 in contact with the blades 50 and 51, respectively, and to the said strips 55 and 56 are secured the ends of the wires 39 and 40. The object of the flexible strips is the 50 same as heretofore referred to in regard to the strips 37 and 38, that is to prevent a break

occurring in the circuit through the excessive vibration of the machine. On the hub of the wheel is mounted a cam 57 which is arranged to come in contact with the switch blade 50 and press it against the contact point 52 on 55 the blade 51, thereby completing the circuit and energizing the electro-magnet at each rotation of the wheels of the machine.

It will be seen from the foregoing description that my device will accurately register 60 and record the distance traveled by the machine and it will also serve for a speedometer for by observing the movement of the hand over the dial and timing it between any fraction of a mile thereon the exact speed at 65 which the machine is moving can be readily ascertained.

What I claim is,—

In a device of the character described, the combination of a circular casing, an electro-magnet mounted in the lower part of said casing below the center thereof, a pivoted armature above said magnet, a pawl carried by said armature, a shaft supported from the rear side of said casing and extending parallel to said rear side above the center of the casing, a ratchet wheel and worm wheel carried by said shaft, said ratchet wheel being adapted to be engaged by said pawl, a second shaft supported at right-angles to the rear wall of the casing at the center of the latter, said shaft having a bevel gear, and a worm wheel adapted to engage the worm wheel on the first named shaft, a third shaft likewise supported from the rear wall of the casing substantially parallel to the rear wall and in line with the center of the casing, said last named shaft having a bevel gear engaging the bevel gear on the second named shaft, a registering device operated by said third shaft, and means for intermittently making and breaking the circuit of said magnet. 75 80 85 90 95

In testimony whereof, I sign the foregoing specification, in the presence of two witnesses.

EZRA NICHOLSON.
